UNITED STATES PATENT OFFICE.

HYMAN MAIMIN, OF NEW YORK, N. Y., ASSIGNOR TO H. MAIMIN COMPANY INCORPORATED, OF NEW YORK, N. Y., A CORPORATION OF NEW YORK.

CLOTH-CUTTING MACHINE.

Application filed July 23, 1925. Serial No. 45,447.

This invention relates to cloth cutting machines of the reciprocating knife type and particularly to means for controlling the presser foot.

- 5 In cloth cutting machines of the reciprocating knife type it is customary to provide a presser foot adjacent the knife which bears down upon the lay of cloth being cut and prevents upward movement of the cloth 10 with the knife. This presser foot is usually supported upon a vertical rod depending from the frame of the machine just in front of the cutting edge of the knife, the presser foot and its supporting rod therefor serving 15 the additional function of a guard. As lays of varying thicknesses are cut from time to time and as the presser foot should always lie upon the lay, it is necessary to provide means for vertically adjusting the 20 position of the foot. This may be done simply by means of a set-screw or by means of a cooperating pawl and rack. But so far as I am aware, in all the arrangements heretofore proposed or used the means for controlling 25 the position of the presser foot have been located on the front of the machine and it has been necessary for the operator to reach around the machine to disengage the presser foot from the frame of 30 the machine and move it manually up or down to make the desired adjustment. Although the adjustment can, of course, be made in this manner it cannot be made without a certain inconvenience and loss of time. 35 It is the object of the present invention to provide means whereby the downward movement of the presser foot can be quickly and simply effected from the handle of the machine, so that in starting to cut a new lay 40 with the presser foot raised above its operative position, the operator can simply release the clamping means and permit the foot to drop freely by gravity upon the lay where it is automatically clamped in operative position. 45
- In carrying out my invention I provide the presser foot with a vertically slideable carriage designed to be moved vertically along a trackway on the frame of the machine. 50 This carriage is provided with a spring-pressed pawl designed to cooperate with a vertical rack carried by the frame of the machine and long enough to engage the pawl in any desired position of adjustment. The
- pawl and rack cooperate to adjustably clamp 55 the presser foot in elevated position. This much of the structure is old and well-known and is described in patent D. S. Maimin, No. 1,207,780, patented December 12, 1916. In accordance with the present invention I 60 mount the rack for a slight horizontal movement away from the pawl, this movement being controlled by an arm extending adjacent the handle of the machine. The operator, by means of this arm, moves the 65 rack inward thereby disengaging the pawl, which is provided with means for preventing further inward movement, and permits the carriage and presser foot to fall by gravity. As soon as disengagement is effected 70 and the foot has dropped, the operator releases the arm and the rack is automatically returned to its initial position in time to receive the pawl in its lower position of adjustment. 75
- In the accompanying drawing I have illustrated a preferred embodiment of my invention. In these drawings, Figure 1 is a side elevation of a cloth cutting machine of the reciprocating knife type equipped with 80 the presser foot control mechanism of the present invention; Figure 2 is an enlarged vertical section through the presser foot carriage and the adjacent part of the machine frame, showing the relation between the 85 pawl, the rack and the means for moving the rack; Figure 3 is a transverse section taken along line 3—3 of Figure 1; Figure 4 is a transverse section taken along line 4—4 of Figure 2; and Figure 5 is an enlarged front 90 elevation of the presser foot carriage.
- The cloth cutting machine illustrated comprises a base 1 from which arises a standard 2 supporting a motor housing 3, a motor 4 and a handle 5. The standard 2 and the 95 housing 3 constitute a support for the other parts of the machine and will be referred to throughout the specification and claims as the frame of the machine. The motor 4 is designed to reciprocate a vertical knife 6 100 which extends through a slot in the standard 2 and serves to cut the cloth in the usual way. The mechanism for reciprocating this knife forms no part of the present invention and will not be described. 105
- Mounted on the front of the frame is a vertical T-shaped trackway 7 upon which slides a carriage 8 carrying the presser foot

9. The presser foot illustrated is of the double separable type illustrated in Patent No. 1,207,780 supported by a pair of guard rods 10 pivotally mounted upon the carriage 5 and integral with a pair of meshing pinions 11. The detailed structure of the presser foot, however, forms no part of the present invention and will not be described here in detail. The presser foot is held in adjusted 10 position by means of a pawl 12 mounted within a housing 13 on the carriage 8 and urged by means of a spring 14 into engagement with a vertical rack 15 held between two halves of the T-shaped trackway 7. The 15 pawl 12 is provided on its inner end with teeth 16 designed to engage similar teeth 17 on the rack and hold the carriage and presser foot at any desired elevation. Disengagement of the pawl and rack may be effected 20 through a pivoted arm 18 provided with a thumb-piece 19. By grasping the thumb-piece 19 and the housing 13 between the thumb and finger, the pawl can be retracted. Inward movement of the pawl is 25 limited by a section 20 of the upper wall of the carriage 8 which serves as a stop for the arm 18. The foregoing construction does not differ materially from that illustrated and described in Patent No. 1,207,780 and by 30 means of it the presser foot can be moved either up or down after disengagement of the pawl in the manner described.

In accordance with the present invention the rack 15 instead of being fixed on the 35 frame is mounted thereon for horizontal or transverse movement, this movement being controlled from the handle of the machine. As illustrated in Figure 2, the rack is provided with a series of diagonal slots 21 through 40 which extend pins 22 fixed to the trackway 7 and hence to the frame of the machine. The lower end of the rack is provided with a pair of spaced jaws 23 which receive between them the forward end of an arm 24 pivoted at 25 and extending rearward toward the handle and terminating in a thumb-piece 26. A spring 27 fixed at one end to the frame of the machine and at the other to the forward end of the arm 24 normally 45 urges this end of the frame upward and hence holds the rack in outward position and in engagement with the pawl 12. In order to release the pawl without reaching around the machine and moving the arm 18, it is 50 only necessary for the operator to push upwardly on thumb-piece 26 of the arm 24, thus moving the rack downward, and, due to the shape of the slots 21, inward, disengaging the teeth 16 and 17 and permitting the 55 carriage and the presser foot to fall by gravity. When pressure on the thumb-piece 26 is removed, the spring 27 immediately returns the rack to its initial position in time to reengage the pawl in its lower position. 60

65 To raise the presser foot the operator grasps

the thumb piece 19 and the housing 13 between thumb and finger, retracts the pawl, and with the same hand raises the carriage 20 and the presser foot.

By means of the construction just described, it is necessary for the operator to employ the arm 18 to disengage the pawl only when the presser foot is to be moved upward. When the presser foot is in raised 70 position and the operator desires to resume cutting or to begin the cutting of a new lay, it is necessary only for him to operate the arm 24 from the handle to disengage the rack and permit the pawl to fall by gravity 75 into operative position. When this position 80 is reached the pawl again engages the rack so that upward movement is prevented.

I claim:

1. A cloth-cutting machine comprising the combination of a supporting frame, a vertically adjustable presser foot, a rack on the frame, a pawl movable with the presser foot designed to engage the rack and hold the presser foot in adjusted position, and means for moving the rack transversely to disengage the pawl and permit the presser foot to fall by gravity. 85

2. A cloth-cutting machine comprising the combination of a supporting frame, a vertically adjustable presser foot, a rack on the frame, a pawl movable with the presser foot designed to engage the rack and hold the presser foot in adjusted position, means for moving the pawl to disengage the rack, and means for moving the rack to disengage the pawl. 95

3. A cloth-cutting machine comprising the combination of a supporting frame, an operating handle, a vertically adjustable presser foot, a rack on the frame, a pawl movable with the presser foot designed to engage the rack and hold the presser foot in adjusted position, means for moving the pawl to disengage the rack, and means operable from the handle for moving the rack to disengage the pawl. 100

4. A cloth-cutting machine comprising the combination of a supporting frame, an operating handle, a vertically adjustable presser foot, a rack on the frame, a diagonal slot 115 in the rack, a pin on the frame of the machine passing through the slot, a pawl movable with the presser foot designed to engage the rack and hold the presser foot in adjusted position, a pivoted arm extending adjacent the handle for moving the rack longitudinally whereby the slot cooperates with the pin to move the rack laterally and out of engagement with the pawl. 120

5. A cloth-cutting machine comprising the combination of a supporting frame, an operating handle, a vertically adjustable presser foot, a rack on the frame, a pawl movable with the presser foot designed to engage the rack and hold the presser foot in adjusted 125 position. 130

- position, means for moving the pawl to disengage the rack, means for moving the rack to disengage the pawl whereby the presser foot is free to drop by gravity, and means 5 for returning the rack into engagement with the pawl after the presser foot has dropped.
6. A cloth-cutting machine comprising the combination of a supporting frame, a vertically adjustable presser foot, a rack on 10 the frame, a spring-pressed pawl movable with the presser foot designed to engage the rack and hold the presser foot in adjusted position, means for moving the rack inward from the pawl, and means limiting 15 the inward movement of the pawl whereby the movement of the rack disengages the pawl.
7. A cloth-cutting machine comprising the combination of a supporting frame, a vertically adjustable presser foot slidably mounted thereon, clamping means movable with the presser foot, an elongated member on the frame cooperating with the clamping means to hold the presser foot at the desired elevation, and means for moving the elongated member out of engagement with the clamping means so that the presser foot may drop by gravity. 20 25

In testimony whereof I affix my signature.
HYMAN MAIMIN.
